UNITED STATES PATENT OFFICE.

HARVEY D. FARRIS, OF SPOKANE, WASHINGTON.

WATER-CLOSET BOWL.

1,349,193.

Specification of Letters Patent. Patented Aug. 10, 1920.

Application filed April 7, 1919. Serial No. 288,179.

To all whom it may concern:

Be it known that I, HARVEY D. FARRIS, citizen of the United States, residing at Spokane, in the county of Spokane and 5 State of Washington, have invented certain new and useful Improvements in Water-Closet Bowls, of which the following is a specification.

This invention relates to improvements in 10 water closet bowls and more particularly to improvements in the clean out devices of such a bowl.

It is customary to provide water closet bowls of the siphon type with clean out 15 openings at the upper ends of their siphoning legs and various constructions of closures for these openings have been devised but many of them possess disadvantages which render their use undesirable and unsatisfactory. To be effective such a closure 20 must be so constructed as to seal the opening in a water and gas tight manner as otherwise, in the flushing of the bowl, there will be a leakage of water past the closure, and 25 when the bowl is not being flushed the accumulated obnoxious sewer gases will escape past said closure. As a consequence, a closure which is not air and water tight is insanitary. Although some types of closures 30 which have been proposed for use might well be adapted to effectually seal an opening of accurately regular contour, it not infrequently happens that in the firing of a porcelain bowl a warping or distortion of the bowl 35 will take place about the clean out opening and however slight this warping or distortion may be, such a closure cannot be applied to the bowl so as to seal the opening in a water and air tight manner. Furthermore, 40 some types of closure which have been proposed for use are so constructed that when tightened in place they will exert certain stresses upon the walls of the bowl tending to fracture the bowl if subjected to other 45 stresses. Other types of closures intended to be made from porcelain present another disadvantage namely, that a bowl so equipped cannot be shipped without liability of fracture of the closure. Also, there are 50 various types of closures which cannot be opened for the cleaning out of the siphoning leg by an inexperienced person and again closed without liability of an ineffective sealing of the closure so that there will be a 55 leakage of water and an escape of gases past the closure. In consideration of the foregoing

ing it is one of the primary objects of the present invention to provide a water closet bowl of the siphon type with a closure for its clean out opening, which closure will be 60 so constructed that when applied within the opening it will effectually seal the opening in a water and gas tight manner even though the opening be of irregular contour because of warping or distortion in the process of 65 manufacture of the bowl; which may be securely fixed in place in a water and gas tight manner without placing any breaking stress upon the wall of the bowl; which may be opened and again closed by the most inexperienced person without detriment to its effectiveness as a sealing medium for the 70 clean out opening and, therefore, without liability of leakage of water and the escape of gas; and which may be shipped applied 75 to the bowl without likelihood of fracture of the bowl because of its presence thereon. It is also an object of the invention to provide a closure for the purpose stated which 80 will in every respect be sanitary and which will possess none of the disadvantages above referred to.

In the drawings:

Figure 1 is a vertical front to rear sectional view through the bowl,

85

Fig. 2 is a detail vertical front to rear sectional view through the forward portion of the bowl illustrating the closure provided for the clean out opening in the front wall of the bowl, and

90

Fig. 3 is a group perspective view illustrating two of the members of the closure in position about to be assembled.

In the drawings, the numeral 1 indicates in general the water closet bowl having the 95 usual flushing channel 2 surrounding its upper margin and provided near its top at its rear side with the usual outlet flushing spout 3 from which water is to be discharged in a downward direction to flow 100 over the bottom of the interior of the bowl so as to carry off the excrement through the upwardly and forwardly inclined siphon leg 4, the excrement passing through the down passage 5 and out through the 105 discharge opening 6 with which is connected the down pipe. In order that the siphon leg 4 and down passage 5 may be cleared of obstructions in the event they become clogged, the front wall of the bowl 110 is formed opposite the juncture of these passages 4 and 5 with an opening 7 normally

sealed in a water and air tight manner by the closure illustrated in Figs. 2 and 3 of the drawings and constituting the present invention. The opening 7 is intended to be truly circular although, as heretofore pointed out, it not infrequently happens, in the firing of the bowls in the process of manufacture, that the wall of this opening will become warped or distorted to a greater or less degree. However, also as pointed out above, this distortion or warping is not a serious detriment in the event the closure embodying my invention is employed and my reasons for making this claim and assertion will be evident from the following specific description of the closure and the manner in which it is secured in place within the opening.

The closure embodying the invention includes in its structure an expanding bushing indicated in general by the numeral 8, this bushing being formed at one end with a flange 9 which is exteriorly threaded as indicated by the numeral 10 for a purpose to be presently explained. The flange is located at the outer margin of one face of the body of the bushing so that an annular shoulder 11 is provided surrounding the opening in the body of the bushing, the wall of this opening being threaded, as indicated by the numeral 12, so as to receive the plug or closure as will be presently pointed out. Except for the threaded portion 10, the body of the bushing is exteriorly smooth and the bushing at its opposite end is formed with a flared or conical flange 13, the outer surface of which merges with the outer surface of the body of the bushing. The numeral 14 indicates in general a gasket of rubber or other suitable packing material which comprises a body portion 15 snugly fitted upon the body of the bushing 8 and provided with a circumferential flange 16 at its outer end, the said flange projecting outwardly from the body portion and the opposite end of the said body portion of the bushing fitting over the inner portion of the flared or conical flange 13, as clearly shown in Figs. 1 and 2 of the drawings. The numeral 17 indicates a ring nut which is threaded onto the flange 9 of the bushing and this nut at its inner face is designed to bear against the outer face of the flange 16 of the packing gasket 14. The flange 13 of the bushing 8 has a maximum diameter substantially equal to the diameter of the opening 7 and in assembling the previously described parts of the closure with the bowl, the said bushing 8 with the gasket 14 in place thereon is fitted with its flange 13 foremost, through the opening 7, so that the body portion 15 of the packing gasket will seat more or less snugly within the opening and the inner face of the flange 16 of said gasket will rest against

the outer face of the bowl. The nut 17 is then applied and tightened and as the nut is tightened upon the bushing, the nut and the flared flange 13 will be brought closer together so that the body portion of the packing gasket will be expanded as it rides up upon the exterior surface of the conical flange and as the said flange is drawn into the gasket. Thus, the body portion of the packing gasket is expanded within the opening 7 and being compressible, is caused to snugly fit within the opening in a water and air tight manner. At the same time, the nut 17 is caused to bear firmly against the flange 16 so as to compress this flange against the outer surface of the wall of the bowl about the opening 7, thus further insuring of a water and air tight fit of the closure within the said opening. The numeral 18 indicates a plug which is exteriorly threaded as at 19 to match the threads 12 of the bushing 8 and this plug is designed to be threaded into place in the opening in the bushing and is provided with a circumscribing flange 20 and has fitted upon it a packing washer 21 which, as the plug is tightened, is compressed between the said flange and the shoulder 11 of the body of the bushing, thus providing an air and water tight fit between the plug and bushing. The plug is provided upon its outer face with a polygonal boss 22 for the application of a wrench or other suitable tool whereby it may be conveniently loosened and tightened. At this point it will be understood that the bushing 8 constitutes a permanent fixture when once fitted into place and is not to be disturbed in the use of the clean out opening, access being had to the passages 4 and 5 within the bowl by removing the plug 18 of the closure.

In order that the closure proper may be concealed from view and to prevent the same becoming fouled with accumulations of filth, a cover cap 23 is preferably provided, this cap being preferably of metal and suitably enameled to correspond in appearance to the enameled surface of the bowl. This cover cap is formed with an opening 24 and a screw or other suitable fastening element 25 is fitted through this opening and threaded into a bore 26 formed centrally in the plug 18.

Having thus described the invention, what is claimed as new is:

1. A closure for the clean out opening of a bowl comprising a bushing having an opening and a circumferential expanding surface, a gasket fitted upon the bushing with the expanding surface entering the gasket, means upon the bushing adjustable to relatively adjust the bushing and gasket to circumferentially expand the latter, and a closure for the opening in the bushing.
2. A closure for the clean out opening of

- 5 a bowl comprising a bushing having an opening and a circumferential expanding surface, an elastic gasket disposed to surround the bushing and to fit about a portion of the said surface thereof, means upon the bushing adjustable to relatively adjust the bushing and gasket whereby to circumferentially expand the gasket, and a closure for the opening in the bushing.
- 10 3. A closure for the clean out opening of a bowl comprising a bushing having an opening and having a portion of its circumferential surface flared, a gasket fitted circumferentially upon the bushing, and means upon the bushing adjustable to relatively adjust the bushing and gasket whereby to expand the gasket as the gasket moves in contact with the flared portion of the bushing, and a closure for the opening in the bushing.
- 15 4. A closure for the clean out opening of a bowl comprising a bushing having a conical flared flange and provided with an opening, a gasket fitted circumferentially upon the bushing, means for relatively adjusting the bushing and gasket whereby the entrance of the flared portion of the bushing into the gasket will serve to expand the latter circumferentially, and a closure for the opening in the bushing.
- 20 5. A closure for the clean out opening of a bowl comprising a bushing circumferentially flared, a gasket disposed to circumferentially fit the bushing and having a circumferential flange, a nut threaded upon the bushing to bear against the flange, and a closure for the opening in the bushing.
- 25 6. A closure for the clean out opening of a bowl comprising a bushing circumferentially flared, a gasket disposed to circumferentially fit the bushing and having a circumferential flange, a nut threaded upon the bushing to bear against the flange, the bushing being provided interiorly with a shoulder and being interiorly threaded, a plug renderably threaded into the bushing, and a packing washer surrounding the plug and confined between a portion of the same and the said shoulder.
- 30 7. A closure for the clean out opening of a bowl comprising a bushing having an opening, means for fixing the bushing within the clean out opening, a closure plug removably fitted within the bushing, a cover cap disposed over the bushing to cover the same, and means for removably securing the cap to the plug.
- 35 8. The combination with a closet bowl having a clean out opening, of a bushing having a flared flange, the bushing being disposed within the opening, a packing gasket surrounding the bushing and a portion of the flange thereof and exteriorly of a diameter to initially fit within the clean out opening, the gasket having a circumferential flange engaging the face of the bowl about the opening, a nut threaded upon the bushing and bearing against the flange whereby to bind the flange against the said face of the bowl and draw the flaring flange of the bushing into the gasket to expand the same within the clean out opening, and a closure for the opening in the bushing.
- 40 9. A closure for the clean out opening of a bowl comprising an annular bushing flared at one end to provide an expanding surface and exteriorly threaded at its other end, a gasket fitted upon and bodily surrounding the bushing between its flared and threaded portions, a nut fitted onto the threaded portion of the bushing to bear against the gasket and cause the same to ride onto the expanding portion of the bushing, and means for closing the opening in the bushing.
- 45 10. A closure for the clean out opening of a bowl comprising an annular bushing exteriorly flared at one end to provide an expanding surface and exteriorly threaded at its other end, a packing gasket bodily fitted onto the bushing and lying between the ends thereof, the said gasket having an outwardly extending flange, a nut fitted onto the expanding surface of the bushing, and a closure for the opening in the bushing.

In testimony whereof I affix my signature.

HARVEY D. FARRIS. [L. S.]
